UNITED STATES PATENT OFFICE.

I ORVILLE WRIGHT, OF BALTIMORE, WILLIAM H. STEM, OF UNION BRIDGE,
AND JOHN H. FARLOW, OF BALTIMORE, MARYLAND.

DRAFT AND BUFFING GEAR OR RIGGING FOR CARS.

SPECIFICATION forming part of Letters Patent No. 739,769, dated September 22, 1903.

Application filed March 14, 1903. Serial No. 147,798. (No model.)

To all whom it may concern:

Be it known that we, I ORVILLE WRIGHT, residing at Baltimore city, WILLIAM H. STEM, residing at Union Bridge, county of Carroll, 5 and JOHN H. FARLOW, a resident of Baltimore city, Maryland, citizens of the United States, have invented certain new and useful Improvements in Draft and Buffing Gears or Riggings for Cars, of which the following is a 10 specification.

The object of our invention is the production of an improved draft and buffing gear or rigging for cars which shall be adapted to embrace as a part thereof, according to the service demanded, a single spring or tandem springs for receiving the main strains of towing and buffing, which shall be comparatively simple in construction and comprised of suitable elements so combined and arranged that 15 repairs may be made when necessary very easily and quickly and without taking the car to the shops, which shall be very strong and capable of withstanding the shocks of severe 20 service, which shall distribute the strains throughout the length of the draft-timbers, which shall admit of the removal and replacement of a coupler and draw-bar without the 25 removal of the spring mechanism, and which shall possess other and desirable novel features of construction constituting the same a 30 superior instrumentality for performing the requisite functions.

With this end and purpose in view our invention consists in certain novelties of construction, arrangement, and combinations of 35 elements and parts hereinafter set forth, and specified in the claims.

The accompanying drawings illustrate two complete examples of the physical embodiment of our invention and a modification of 40 the tandem-spring arrangement constructed according to the best modes we have so far devised for the practical application of the principle.

Figure 1 is a longitudinal sectional view in elevation of the draft and buffing gear with tandem springs. Fig. 2 is a half top plan view and half horizontal section of the draft-timbers and other parts of the gear. Fig. 3 45 is a cross-section. Fig. 4 is one of the draft-timber-reinforcing plates. Figs. 5, 6, and 7

are views similar to Figs. 1, 2, and 3, but illustrating the invention in connection with a single or compound spring. Fig. 8 shows one of the follower-pieces used with the tandem 55 spring. Fig. 9 is an end view of Fig. 8. Fig. 10 illustrates a modified construction of the tandem springs in connection with an integral follower pin and boss.

Referring to the several figures of the drawings, the numeral 1 designates the central stringers of the car-body; 2, the end sill; 3, the buffer-block; 4, the draft-timbers; 5, the bolts which secure the draft-timbers to the stringers; 6, elongated slats in the draft-timbers; 7, the central slots in the draft-timbers; 8, the draft-timber plates; 9, elongated slots at the ends of the plates; 10, the central slots; 11, lugs surrounding the slots and adapted to be seated in the draft-timbers; 12, bolts 60 which secure the plates to the draft-timbers; 13, the chafing-plate; 14, the carry-iron; 15, the bolts which pass through the carry-iron, the chafing-plate, and the buffer-block; 16, the draw-bar yokes; 17, the end slots in the 75 yokes; 18, the central elongated slots; 20, the draw-bar of the coupler; 21, an elongated slot in the draw-bar; 22, the front follower-block; 23, an elongated slot in the block; 24, a recess in the end of the block; 25, the rear follower-block; 26, a slot in the block; 27, a recess in the end of the block; 28, equalizing 80 pieces which are located in the slots of the draft-timbers, plates, yokes, blocks, and draw-bar and which are held in place by cotters; 85 29, a fixed abutment between the tandem springs; 30, bolts which anchor the abutments; 31, an open space at the center of the abutment; 32, loose follower-plates, and 33 the tandem springs. 90

In Figs. 1, 2, 3, 8, and 9 the numeral 35 designates the front follower-pin; 36, the rear follower-pin; 37, the heads of both pins, which two pins are of the same construction; 38, slots in the heads of the pins; and 39 represents the slots in the bodies of the pins. The space from *a* to *b* is open, as shown in each pin. The slots 38 are approximately one and three-fourths inches in length and indicate the distance which one pin can move upon 100 the other. We have shown three slots 38 and three slots 39; but any number may be used, 95

the purpose of the construction being to hold the adjacent ends of the pins in line and to allow one to travel upon the other.

In Fig. 10 the numeral 40 designates an integral follower-pin, and 41 a central boss of larger diameter than the body of the pin and which boss bears against the follower-plates.

In Fig. 5 we show a single or compound 10 spring 42, held between the follower-blocks by lugs 43, integral with the ends of the blocks.

The *modus operandi* of the first example is as follows: In drawing the outward motion of the draw-bar is imparted to the front and 15 rear equalizing-pins, the yokes, the rear follower-block, the rear follower-pin, and the front follower-plate simultaneously. The front follower-block and the rear follower-plate are immovable and form abutments for 20 the springs. As the front and rear equalizing-pins move forward in the slots, the yokes move over the central equalizer-pin, the head of the rear follower-pin moves longitudinally of the front follower-pin, carrying 25 with it the front follower-plate, and consequently compress both the tandem springs equally. When the front and rear equalizing-pins reach the ends of the slots, they impart 30 all the additional strains to both the front and rear ends of the draft-timbers, thus distributing the said strains instead of concentrating them at a single point. The compression of the springs in this example is approximately one and three-fourths inches; but it 35 may be varied, if so desired, at the will of the constructors of the rigging. In buffing the operation is substantially the same. The slot in the draw-bar moves over the front equalizing-pin, the front follower-block moves 40 over the central equalizing-pin, the head of the front follower-pin moves over the head of the rear follower-pin, the rear follower-plate moves rearwardly, and both the springs are compressed until the end of the draw-bar 45 and the front follower-block reach the limit of their travel, when all additional strains are imparted through the medium of the front and central equalizing-pins to the draft-timbers. It will be observed that both the springs 50 are equally compressed and that the extent of compression is determined by the length of the slots in the draw-bar and in the front follower-block.

In the example shown by Figs. 5, 6, and 7 55 the mode of operation is substantially the same as in the first example. When drawing, the front follower-block serves as an obstruction for the spring, and it is compressed to the extent of the forward movement of the 60 front and rear equalizing-pins within the slots. In buffing the rear follower-block is immovable and constitutes the abutment for the rear end of the spring. Fig. 10 shows a modified construction in which the front and 65 rear tandem springs are unequally compressed in both drawing and buffing. In drawing the rear follower-block first com-

presses the rear spring until the bottom of the recess 27 in the block strikes the end of the follower-pin 40. Then the pin moves forward 70 the boss 41, carrying with it the front follower-plate, till the front end of the pin is seated within the recess 24 of the front follower-block. As shown in this case, the rear spring is compressed one and three-fourths 75 inches and the front spring seven-eighths of an inch. The same operation takes place, as is obvious, in the act of buffing, except that the front spring is compressed twice the distance of the compression of the rear spring. 80 It is clear that by shifting the follower-pin to the front or rear and also the abutment the degree of compression of the springs may be varied. For instance, if the pin and abutment be located seven-eighths of an inch toward 85 the front the rear spring only would be compressed in drawing and both springs be compressed in buffing, and vice versa.

The method of assembling the several parts and elements of the gear and the method of 90 replacing a part or element will readily be understood by any person skilled in the art upon an inspection of the drawings, and therefore the same need not be specially set forth.

While we have illustrated and described 95 only two complete examples of the physical embodiment of our invention and one modified arrangement of the spring mechanism, we do not thereby intend to limit the scope thereof to such embodiments, inasmuch as the 100 principle may be applied by other modes. For the two specific follower-pins 35 and 36 may be substituted other pins, which will be of different constructions, but perform like functions. Metallic draft-timbers may be 105 used in place of those shown, either made separate or integral, the shape of the follower-blocks altered, and many other modifications, substitutions, omissions, additions, and changes be introduced at the will and choice 110 of the manufacturer without constituting substantial departures.

What we claim as new, and desire to secure by Letters Patent, is—

1. The combination in a draft and buffing 115 gear having slots, of a coupler and draw-bar; a front follower-block; a rear follower-block; a spring or springs between the blocks; slotted yokes; and equalizing-pins a plurality of which are movable within slots of the gear. 120

2. The combination in a draft and buffing gear having slots, of a coupler and slotted draw-bar; a front follower-block with an elongated slot; a rear follower-block; a spring or 125 springs between the blocks; yokes; and equalizing-pins; the slots in the draw-bar and front follower-block being adapted to move over two of the pins during the act of buffing.

3. The combination in a draft and buffing gear, of a coupler and draw-bar; a front follower-block; a rear movable follower-block; a spring or springs between the blocks; yokes 130 each having an elongated slot; equalizing-pins; and slotted supports for the pins; two of

- said pins being adapted to move within slots; and the elongated slots of the yokes to move over a pin during the act of drawing.
4. The combination in a draft and buffing gear, of a draw-bar and coupler; supports having two elongated slots; two movable pins in the slots; a central equalizing-pin; two slotted yokes the central slots being elongated; a slotted follower-block; a rear follower-block; and a spring or springs between the follower-block; said draw-bar being provided with an elongated slot and within which is located an equalizing-pin.
5. The combination in a draft and buffing gear, of a coupler and draw-bar; a slotted follower-block in the rear of the end of the draw-bar; a rear follower-block; a spring or springs between the blocks; slotted supports or draft-timbers; slotted yokes; and equalizing-pins within the slots of the draw-bar, blocks, yokes, and supports; the central equalizing-pin being fixed and immovable, and the slotted yoke transmitting motion to the rear equalizing-pin when the draw-bar is advanced in drawing.
6. The combination in a draft and buffing gear, of a coupler and draw-bar; slotted supports; follower-blocks; slotted yokes; equalizing-pins supporting the yokes; tandem springs; and means for supporting the tandem springs; said slotted yokes being located between the slotted supports and the follower-blocks and serving to transmit motion from the draw-bar to the rear equalizing-pin.
7. The combination in a draft and buffing gear, of a coupler and draw-bar; slotted supports; follower-blocks; slotted yokes; equalizing-pins which support the yokes; tandem springs; and a follower-pin in connection with the tandem springs; the central equalizing-pin being fixed, and the other equalizing-pins being movable.
8. The combination in a draft and buffing gear of slotted supports; a rear follower-block; a front follower-block; slotted yokes; a slotted draw-bar; equalizing-pins; tandem springs between the follower-blocks; a fixed abutment; follower-plates each side of the abutment; and a follower-pin having a boss adapted to engage the follower-plates.
9. The combination in a draft and buffing gear, of slotted supports; a rear follower-block; a front follower-block; slotted yokes; a slotted draw-bar; equalizing-pins; tandem springs between the follower-blocks; a fixed abutment; follower-plates each side of the abutment; and two follower-pins, one of which is movable relative to the other.
10. The combination in a draft and buffing gear, of slotted supports; a rear follower-block; a front follower-block; slotted yokes; a slotted draw-bar; equalizing-pins; tandem springs between the follower-blocks; a fixed abutment; follower-plates each side of the abutment; and two follower-pins, each having a slotted head and slots in the body thereof, whereby one head may move relative to the other.
11. The combination in a draft and buffing gear, of supports having slots two of which are elongated; a rear follower-block supported by an equalizing-pin passed through the block and with its ends in the elongated slots of the supports; a front slotted follower-block with an equalizing-pin passed through the slot and with its ends in the slots of the supports; a spring or springs between the follower-blocks; a coupler and draw-bar; and means connecting the draw-bar with the rear follower-pin whereby motion may be imparted to the rear follower-block.
12. The combination with a draft and buffing gear, constructed substantially as set forth, of a draw-bar; springs; follower-blocks; two slotted yokes; slotted supports; pins; and said yokes being located between the slotted supports and the draw-bar and spring or springs.
13. The combination with a draft and buffing gear, substantially as described, of draft-timbers and plates 88, each having elongated end slots 9 and a central slot 10, for the reception of two movable and one immovable equalizing-pins; and said slots having lugs 11, serving as bearings for the pins.
14. The combination with a draft and buffing gear, in substance as set forth, of supports having slots one of which is elongated; two slotted follower-blocks one of which slots is elongated; equalizing-pins in the slots of the blocks and supports; a spring; a draw-bar 100 and coupler; and slotted yokes connected with the draw-bar for moving the blocks and compressing the spring.
15. The combination in a draft and buffing gear, of supports each having three slots; a draw-bar with an elongated slot; a follower-block in the rear of the draw-bar and having an elongated slot; a slotted rear follower-block; a spring between the follower-blocks; slotted yokes located each side of the follower-blocks, one of said slots being elongated; and three equalizing-pins within the slots of the several slotted elements; the central pin being fixed and the end pins movable within the slots.
16. The combination in a draft and buffing gear, of supports each having three slots; a draw-bar with an elongated slot; a front follower-block in contact with the end of the draw-bar and having an elongated slot; a slotted rear follower-block; a spring between the follower-blocks; two yokes each having three slots, the central one elongated; and three equalizing-pins within the slots of the several slotted elements; the middle pin being immovable; and the end pins movable, and when the parts are assembled occupying the rear portions of the elongated slots in the supports.
17. The combination in a draft and buffing gear, of slotted supports; slotted follower-blocks located between the supports; a spring between the follower-blocks; two slotted yokes located between the supports and one

on each side of the follower-blocks; and a coupler and draw-bar.

18. The combination in a draft and buffing gear, of slotted supports, the rear slots elongated; a rear follower-block with a slot; slotted yokes between the supports and one on each side of the follower-block; a spring in front of the follower-block; a movable pin passed through the rear slots in the supports, the follower-block, and the rear slots in the yokes; a fixed pin located within the slots of the supports and the slots of the yokes; and

a draw-bar and coupler; the front ends of the yokes being secured to the draw-bar, and said yokes movable relative to the fixed pin. ¹⁵
